UNITED STATES PATENT OFFICE.

HENRY A. ARMSTRONG, OF BROOKLYN, NEW YORK, ASSIGNOR TO INTERNATIONAL TYPESETTING MACHINE COMPANY, OF NEW YORK, N. Y., A CORPORATION OF NEW YORK.

LINE-STOP FOR LINE-CASTING MACHINES.

1,108,825.

Specification of Letters Patent. Patented Aug. 25, 1914.

Application filed January 4, 1913. Serial No. 740,250.

To all whom it may concern:

Be it known that I, HENRY A. ARMSTRONG, a citizen of the United States, residing at Brooklyn, in the county of Kings and State 5 of New York, have invented new and useful Improvements in Line-Stops for Line-Casting Machines, of which the following is a specification.

This invention relates to improvements in 10 line casting machines of the linotype class and more particularly to the matrix handling and transferring mechanism.

The primary object of the invention is to provide an automatic stop against which 15 the line of matrices abut when they enter the first elevator and while the line of matrices is being carried by such elevator to the casting position, such stop serving to prevent turning or other displacement of the matrices and accommodating itself automatically 20 to lines of different lengths, thereby enabling the machine to be adjusted for lines of different lengths without requiring manual adjustment of the stop by the operator.

25 To these and other ends, the invention consists in certain improvements, and combinations and arrangements of parts, all as will be hereinafter more fully described, the 30 novel features being pointed out particularly in the claims at the end of the specification.

In the accompanying drawings:—Figures 1, 2 and 3 show one form of the invention applied to the first elevator of a line casting machine, Fig. 1 showing the device in front elevation with parts in section, Fig. 2 being a perspective of the upper portion of the first elevator with the stop applied there- 40 to; and Fig. 3 is a perspective view of the line stop removed from the elevator; Figs. 4 and 5 show another embodiment of the invention; Fig. 4 representing a transverse section through the jaws of the first eleva- 45 tor; and Fig. 5 a perspective of the stop and the line transfer slide.

Similar parts are designated by the same reference characters in the several views.

The invention in the present instance is 50 shown applied to a line casting machine of the well known linotype class wherein each line of matrices is composed by manipulation of the keyboard and delivery mechanism operates to convey the line of matrices longitudinally into what is commonly known

as the first elevator. This elevator embodies a slide 1 having an overhanging head to which a jaw 2 is fixed, a coöperating jaw 3 being arranged opposite to the jaw 2 and is fixed to and spaced therefrom by an inter- 60 posed block 4. These opposed jaws provide a channel or passageway for the matrices M, and in the construction shown, the elevator is capable of receiving matrices when assembled at two different levels whereby either 65 of two characters on each matrix may be used. The opposed faces of the jaws which constitute the walls of the passageway are in the present instance channeled at 5 and 6 to receive the lugs at the upper corners of 70 the matrices, these channels forming ledges 7 and 8 which coöperate with the lugs of the matrices assembled at the lower level, thereby supporting these matrices. A rail 9 is fitted into the lower portion of the jaw 2 75 and serves to support the matrices assembled at the upper level, this rail being capable of retraction to permit the matrices at the upper level to drop to the lower level preparatory to the transfer of the line of matrices 80 from this elevator to the matrix-distributing mechanism. In the operation of machines of this class, the delivery mechanism conveys the line of matrices into the first elevator while the line is confined in an endwise direction, whereupon the elevator lowers the line of matrices to the casting position. 85 While the elevator is carrying the line of matrices from the delivery mechanism to the casting position, the delivery mechanism cannot operate to prevent turning or other displacement of matrices in the line. Experience has shown it to be desirable to provide stops on the first elevator to coöperate with both ends of the line of matrices 90 for the purpose of preventing displacement of the matrices, due to jar of the machine or other causes. It is customary to employ either one or a pair of spring-operated detents 10 at one end of the first elevator to 95 prevent the end matrices in the line from falling back after the line has been delivered to the elevator. The present invention provides an automatically adjustable stop for the opposite end of the line of matrices whereby the line of matrices is confined in such manner as to prevent displacement thereof.

In the construction shown in Figs. 1-3 inclusive, a stop 11 is used, this stop embody- 100

110

ing a pair of side members 12 and 13 which are adapted to fit and slide longitudinally in the channels 5 and 6 of the elevator jaws. Preferably, the friction between the side members of the stop and the jaws of the elevator is utilized to retain the stop in operative position. The side members of the stop are preferably connected at one end while they are unconnected at the opposite end of the elevator, forming an open passageway between them, as shown. The line of matrices when introduced into the second elevator abuts against the ends of the side members 12 and 13 at the open ends thereof, the stop being pushed to the left in Fig. 1 as the line of matrices enters the elevator. According to the present invention, this stop is automatically reset after each operation by the slide which transfers the line of matrices to the distributing mechanism after the cast has been made. This slide 14 may be of the usual construction, it being shown as mounted to operate in the guide 15 and provided with the usual link 16 for reciprocating it at appropriate intervals. The stop for the line of matrices is provided with a longitudinal bar 17 which may be formed as a part thereof, and said bar is slidable in a slot 18 formed in the top of the elevator jaw 3 and is provided with an operating projection 19 which is exposed above said jaw. The line transfer slide 14 is provided with the usual member 20 which serves to push the line of matrices out of the elevator and into the distributing mechanism, and said slide is also provided with an arm 21 which is fixed thereto and provided with a hook 22 which, when the line transfer slide moves to the right in Fig. 1 to remove a line of matrices from the elevator, co-operates with the projection 19 of the line stop and carries said stop toward the right in readiness to be engaged and pushed toward the left by the next incoming line of matrices, the stop being retained in the position to which it is advanced by the line of matrices by reason of the frictional engagement between the stop and the elevator. In order that the elevator may descend while the line transfer slide is at the receiving end of the elevator, the arm 21 preferably extends upwardly from the slide in rear of the elevator jaw 3, thence extending forwardly, and thence downwardly through the space between the elevator jaws.

The construction shown in Figs. 4 and 5 enables a relatively shorter line stop to be used as compared with that shown in Figs. 1-3 inclusive. In this instance, the line stop 23 embodies side members 24 and 25 which operate frictionally in the channels 5 and 6 of the elevator jaws, and the line delivery slide 27 carries an arm 28 which is pivoted on a pin 29 supported by the slide, and a spring 30 operates to yieldingly hold the

arm in a horizontal position and in line with the stop 23. In this construction, the stop is moved toward the right hand matrix-receiving end of the elevator by the arm 28 when the line delivery slide 27 moves in said direction to transfer the line of matrices from the elevator to the distributing mechanism after a cast has been made from that line and the next incoming line of matrices engages and pushes the stop toward the left, the stop remaining in the position to which it has been advanced by the matrices owing to the frictional engagement between the stop and the elevator, thus preventing turning or other displacement of the matrices. The elevator may descend to convey the line of matrices to the casting position before the line delivery slide returns to its initial left-hand position, the arm 28 being deflected downwardly by the elevator jaw 3, as shown in Fig. 4, and thus permitting descent of the elevator without interference.

In both forms of the invention, each line of matrices is held or confined at both ends while the elevator is conveying the same to the casting position, dropping back of the matrices at the rear end of the line being prevented by the detent or detents 10 while turning or other displacement of the matrices at the forward end of the line is prevented by the movable stop. This stop is particularly useful in connection with machines of the linotype class which embody means for adapting the same for the composition and casting of lines of different lengths, as the stop accommodates itself automatically to the length of the line and hence requires no setting or manual adjustment by the operator when the length of the line is changed, and the stop is automatically moved toward the receiving end of the elevator preparatory to the reception of each line of matrices and will be advanced by the incoming line of matrices a distance determined by the length thereof.

I claim as my invention:

1. In a machine of the linotype class, the combination of the first elevator, a line stop reciprocable in the matrix channel of the elevator adapted to be advanced by an incoming line of matrices, and means for moving the stop toward the receiving end of the elevator preparatory to the reception of a line of matrices.

2. In a machine of the linotype class, the combination with the first elevator, of a line stop frictionally engaging the elevator and adapted to be engaged and advanced by an incoming line of matrices, and means for moving the stop in the matrix channel and toward the receiving end of the elevator when a line of matrices is removed from the elevator.

3. In a machine of the linotype class, the combination with the first elevator and the

line transfer slide, of a line stop reciprocable in said elevator, and means for engaging the transfer slide with the line stop to move the latter to the receiving end of the elevator.

5 4. In a machine of the linotype class, in combination with the first elevator, a line stop reciprocable in the matrix channel of said elevator having a normal position at the receiving end of the elevator and adapted to be moved out by the incoming matrices, and automatic means for returning said line stop to its normal position.

10 5. In a machine of the linotype class, the combination with the vertically movable first elevator and the coöperative line delivery slide, of a line stop movably carried by the

elevator and adapted to be advanced to different positions by an incoming line of matrices, and means for connecting said stop to the line delivery slide when the elevator 20 is in elevated position whereby the operative movement of said slide will automatically move the line stop toward the receiving end of the elevator.

15 In testimony whereof I have hereunto set 25 my hand in presence of two subscribing witnesses.

HENRY A. ARMSTRONG.
